(57) **CLAIM**

The ornamental design for a magnetic buckle, as shown and described.

DESCRIPTION

FIG. 1 is a perspective view of a magnetic buckle of the subject disclosure;

FIG. 2 is a front view thereof;

FIG. 3 is a rear view thereof;

FIG. 4 is a right view thereof;

FIG. 5 is a left view thereof.

FIG. 6 is a top view thereof; and,

FIG. 7 is a bottom view thereof.

The broken lines illustrate portions of the magnetic buckle and form no part of the claimed design.

1 Claim, 5 Drawing Sheets
